[57] CLAIM

The ornamental design for two piece produce box, substantially as shown and described.

DESCRIPTION

FIG. 1 is a top plan view of a two-piece produce box showing our new design;

FIG. 2 is a bottom plan view thereof;

FIG. 3 is a side elevational view thereof, with the other side elevational view being the mirror image thereof; and

FIG. 4 is an end elevational view thereof, with the other end elevational view being the mirror image thereof.
